MEANS FOR FINISHING LAUNDERED SHIRTS

Leland R. Morse, Chicago, Ill.

Application June 7, 1937, Serial No. 146,797

1 Claim. (Cl. 223—37)

This invention relates to improvements in the means for finishing shirts in laundries and preparing them for delivery, and more particularly to an assembly table in which the laundered shirt board and shirt band are assembled as the shirt is folded and finished on the table.

Heretofore, laundered shirts have been finished upon a table having an opening of sufficient size to receive the neck-band of a collarless shirt or the collar attached to a shirt during the folding operation, referred to above. It has also been customary to put the finishing touches by a hand-operated iron on a freshly laundered shirt spread back down upon such a table, then by 10 grasping the shoulders of the shirt reverse it upon the board with the collar received within the table opening, place the shirt board, if one is used, longitudinally along the center of the shirt, fold the sleeves and sides over each other, 15 and fold the tail upon the body to complete the fold. The collar being received within the table opening not only prevents the collar neck-band from becoming rumpled during the folding but also positions and anchors the shirt during the 20 folding process.

It is an object of this invention to provide a shirt finishing table having a collar-receiving opening, such as above described, with additional means for carrying out a novel method of folding a laundered shirt over a shirt board in conjunction with a shirt band or wrapper having a cut-out notch to accommodate the collar neck-band to assemble a laundry package as disclosed in my former Patent No. 2,026,645, of January 7, 30 1936. It is also an object of this invention to provide such a shirt finishing table with a means for retaining and positioning a supply of shirt bands or wrappers, shirt boards and collar supports in a manner most convenient to the operator to reduce the movements and increase the 35 efficiency of the operator in assembling the shirt package.

With these and other objects in view reference is made to the accompanying sheets of drawings 40 illustrating an embodiment of this invention, with the understanding that minor changes may be made without departing from the scope thereof.

In the drawings:

Figure 1 is a top plan view of a shirt finishing and assembling table, including the improvements of this invention.

Figure 2 is a view in vertical section taken on the line 2—2 of Figure 1 looking in the direction of the arrows.

Figure 3 is a fragmentary top plan view of the assembly table illustrating the first step in the folding of a shirt thereon.

Figure 4 is a fragmentary view in perspective illustrating another step in the folding of a shirt. 5

Figure 5 is a fragmentary top plan view of the assembly table illustrating another step in the folding of a shirt.

Figure 6 is a similar view illustrating the folded shirt about to be detached from the holding 10 means.

Figure 7 is a view in perspective illustrating a shirt folded in the manner illustrated in Figures 3 to 6, inclusive.

Figure 8 is a detail plan view of the shirt band 15 or wrapper illustrated in Figures 3 to 7, inclusive.

In folding a freshly laundered shirt into a laundry package in accordance with this improved method, it is preferable to employ a shirt assembly table, as illustrated in Figures 1 and 2 20 of the drawings. This table includes an oblong flat surface upon which the shirt may be spread, and, if desired, finished by hand. The table body

1 may be supported on legs 2 or may be provided with transverse supports 3 adapted to rest upon another table and space apart the body 1 therefrom to clear the attachments upon the underside thereof. It is preferable to provide a collar recess 4 adjacent the left edge of the body 1 25 on the side of the longitudinal center line nearest the operator and also a rectangular opening 5 adjacent the same end and adjacent the edge of the table opposite the operator for receiving a commercial label or strip moistening device. A shirt band or wrapper, shirt board, and collar 30 protector receptacle 6 is preferably detachably mounted upon the end of the table adjacent the collar recess 4. Tables of this character are preferably covered with a pad which requires replacing about every six months. The pad 35 must be cut out to correspond to the collar recess 4 and moistening machine opening 5. It is preferable to provide a metallic member 7 corresponding in shape to said openings having an outturned flange 8 so that when the member is 40 inserted in the opening the flange will hold the pad in place upon the upper surface of the table body. If desired, an opening 9 may be provided in the table for receiving a dampening device for moistening the cloth used in finishing 45 the shirt by hand, and this requires a similar opening to be made in the pad and a member 7 with a flange 8 similar to the collar recess member 7 and flange 8, shown in Figure 2 which may be inserted in the opening for the dampening 50

55

55

55

device and hold the pad in the same manner as heretofore described. A sadiron support 10 may be secured in any desired manner upon the upper side of the pad. When the dampening device and 5 sadiron are employed, the aperture and stand therefor are arranged adjacent the right edge of the table with the dampening device in the corner most distant from the operator.

The collar recess 4 is sufficiently large to receive the largest size collar attached to a shirt and is provided with a collar anchor in the form of a block 11 arranged centrally within the collar recess and preferably mounted upon a bar 12 secured to the underside of the table body 1. An 15 aperture 13 is also provided through the table body 1 between the edge of the collar recess 4 and the left edge of the table providing a passageway for a flexible member or cord 14 attached upon the upper side of the table to a clip or clamp 15 and at the opposite end to a counter-weight 16.

The receptacle 6 is preferably made of metal and provides separate compartments for shirt bands 17, shirt boards 18, and collar supports 19, 25 one above the other in the order named.

As the shirt bands or wrappers are generally a standard length of nineteen inches and of various widths this compartment is constructed to be of sufficient size to receive the band with its 30 longest side parallel to the adjacent end of the table, and, therefore, the depth of this receptacle will vary in accordance with the widths of the bands and be of such depth that the longitudinal edge of the band adjacent the table end will 35 project slightly beyond the upper end of the receptacle. The opposite end of the receptacle is closed at an angle so that the succeeding bands will each project over the edge of the one below it, as shown in Figure 2. The compartment for the shirt boards 18 is preferably divided in two 40 sections. The shirt boards 18 are generally of a standard size of eight inches by sixteen inches and the compartments are of such size as to receive the boards lengthwise with the edges extending slightly beyond the open end with the 45 opposite end closed at an angle so that the edges of the succeeding boards will each extend over the edge of the one below it, as shown in Figure 2. Most laundry packages include a cardboard 50 collar support of some kind. The lower compartment provided for the collar supports is preferably divided into three sections and is of less width than the two sections thereabove. The 55 collar supports 19 are usually flat strips and the receptacle is of such size that the lowermost strip will extend slightly beyond the open end thereof and the rear end closes at an angle so that the edge of each succeeding strip will project beyond the edge of the one below, as shown in Figure 2.

It is preferable to attach the receptacle 6 by 60 means of two parallel spaced-apart supports 29 extending from and secured to the under surface of the table body 1 having a transverse connecting bar 21, whereby the bottom of the board compartment 18 will rest upon the ends of the parallel supports 29 and the closed end of the collar support compartment 19 engage the transverse support 21 between the parallel bars with the bottom of the open end resting upon the end of 65 the table, as shown in Figure 2.

By the construction of the assembly table just 70 described, a laundered shirt may be folded in accordance with this invention with the least manual movement on the part of the operator. 75 The shirt is first placed upon the board with

the sleeves spread out lengthwise of the board and with the collar on the upper side. The operator then removes the top shirt band wrapper 17 from the receptacle 6 and places it over the shirt with the cut-out portion 17a passed under the points of the collar to engage the shirt band and the sleeves folded parallel to the sides, as shown in Figure 3. The shirt with the band 17 is then reversed, as shown in Figure 4, and the collar of the shirt placed in the collar recess 4. 10 A shirt board 18 is then taken from the receptacle 6 and placed centrally of the shirt with the short left-hand edge adjacent the outer edge of the collar band and the shirt sleeves are then folded in and the sides of the shirt are lapped 15 over the board. The lapped edges of the shoulders are drawn sufficiently together to cause the board 18 to bow outwardly. The clip 15 is then engaged with the lapped shoulder portions, as shown in Figure 5. This clip 15 holds the board 20 bowed while the tail of the shirt is folded up over the opposite end of the board and the opposite edges of the shirt band or wrapper 17 lapped over each other. The operator then removes from the moistening machine in the opening 5 a moistened label or a moistened strip or 25 tape 17B and secures the overlapped edges of the shirt band together. By grasping the end of the finished package opposite the collar the shirt may be detached from the clip 15 by a 30 quick upward and outward movement, as shown in Figure 6, and the laundry package is ready for transportation or storage, as shown in Figure 7.

If the shirt is to be finished manually, of course, it is to be understood that a moistening device is placed in the opening 9 and a sadiron support 10 will be attached to the table body.

From the above description it is readily seen that by the employment of a shirt assembly table, such as above described, the shirt can be folded into the improved laundry package as disclosed in my said prior Patent No. 2,026,645 of January 7, 1936, most efficiently and with less expenditure of effort on the part of the operator, which increases the efficiency and capacity of the operator.

When the shirt is detached from the clip 15 the counter-weight 16 automatically returns the clip to the surface of the table and holds it so that it will not obstruct the folding of the next shirt. The collar-positioning block 11 anchors the shirt as it enters into the aperture formed by the collar and prevents the shirt from slipping around during the folding process. It is to be noted that the receptacle 6 presents first the shirt band wrapper 17, the removal of which is the first step in this method of folding the shirt. The board 18 is supported just below the shirt band and is the next article removed from the receptacle in folding the shirt. If it is desired to use a collar support 19, it is applied after the package has been completed as the last step in this method, and the collar supports 19 are contained in the receptacle under the shirt boards 18, whereby each article in the receptacle is positioned in the order in which it is used by the operator.

While the collar support has been described above as being inserted as the last operation, in some cases, it may be inserted as the first step in the folding of the shirt.

What I claim is:

A finishing table for laundered collar-attached shirts having an opening in the top adjacent one 75

end for receiving the collar and positioning the shirt when the front of the shirt is laid upon the table, and a releasable clip secured at one end of a cord passing through the table between 5 the collar opening and the adjacent end, said cord having retractile means upon its other end to normally hold the clip in engagement with the table top and allowing the clip to be extended to

engage the shoulder portions of the shirt after the sides and shoulders are folded over a shirt board and hold the shirt in position until a shirt band has been applied to bow the shirt board and secure the shoulder portions in overlapped 5 relation.

LELAND R. MORSE.
